(57) **CLAIM**

The ornamental design for a practice alignment device, as shown and described.

DESCRIPTION

FIG. 1 is a top elevated perspective view of a practice alignment device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof.

FIG. 8 is a top an elevated, perspective view of the device in an extended configuration; and,

FIG. 9 is another a front view thereof of the device in an extended configuration.

The broken lines shown in the drawings illustrate portions of the practice alignment device that form no part of the claim.

1 Claim, 6 Drawing Sheets
